EGIDIO DELIA AND VINCENT CORRADO, OF NEW YORK, N. Y.

FAN FOR SEWING MACHINES.

1,417,470.

Specification of Letters Patent. Patented May 23, 1922.

Application filed July 27, 1920. Serial No. 399,293.

To all whom it may concern:

Be it known that we, EGIDIO DELIA, a subject of the King of Italy, and VINCENT CORRADO, a citizen of the United States, both 5 residing at New York city, borough of Manhattan, in the county and State of New York, have invented a certain new and useful Improved Fan for Sewing Machines, of which the following is a specification.

10 This invention relates to fans adapted to be associated with a sewing machine fly wheel in such manner that during the operation of the machine, the fan will supply air in motion to the operator, thereby rendering 15 her activities more comfortable and less irksome in hot weather.

It has been heretofore suggested to associate a fan with a sewing machine, but in the prior constructions the fan has either 20 been entirely without protection, or provided with a guard supported on the base of table of the machine. As the fan is usually positioned directly adjacent the fly wheel, to which the operator, in hand operated machines, finds occasion to frequently apply 25 the hand, such fans, unless properly protected or guarded are a menace to the operator's hands, and, accordingly, in the majority of cases have been covered with a 30 suitable guard. In every instance, so far as we are aware, these guards have been supported upon the table of the machine in such manner that they unduly encumber the 35 table and are large, cumbersome and unsightly. Moreover, in many instances, the guard does not fulfill its function in that it does not properly protect the hands of the operator against engagement with the operating parts.

40 The object of the present invention is to provide fans of the general character specified adapted to be associated with the fly wheel of a sewing machine in a compact and uncumbrous manner, and so constructed that the guard of the fan will be carried by the fan in a compact manner, leaving the table entirely unencumbered, while fully protecting the hands of the operator against danger from the blades of the 45 fan.

Features of the invention, other than those specified, will be apparent from the herein-after detailed description and claim, when

read in conjunction with the accompanying drawings.

The accompanying drawings illustrate one practical embodiment of the invention, but the construction therein shown is to be understood as illustrative, only, and not as defining the limits of the invention.

Figure 1 illustrates the end of a sewing machine, showing a fan embodying the present invention associated therewith; and,

Figure 2 is a perspective view of the fan of this invention.

Referring to the drawings, 1 designates the frame of the machine, provided with the usual fly wheel 2, adjacent which is positioned the customary pulley 3 with which a belt, not shown, cooperates in the driving 70 of the machine. The fly wheel 2 or pulley 3 is usually provided with a hub 4 which projects beyond the pulley 3 as shown in Figure 1. In accordance with this invention, the fan is adapted to be secured to this 75 hub.

The fan which is shown in perspective in Figure 2 embodies a hub 5 from which radiate a plurality of blades 6 secured to the hub of said fan in any suitable manner. The 80 hub 5 of the fan is split for a portion of its length and is provided with upstanding apertured ears 7, through which is adapted to be passed a bolt 8. By thus constructing the hub 5, it is rendered adjustable as 85 to diameter and is adapted to be slipped over the hub 4 of the fly wheel and clamped in place by tightening the bolt 8 to be thereby firmly held in position upon the hub of the fly wheel, so that when the machine is operated, the fan is simultaneously rotated to 90 deliver a current of air to the operator working at the machine.

In order to protect the hands of the operator against engaging with the blades 6 and 95 being hurt or injured thereby, an annular ring 9 is positioned peripherally of the fan and secured to the outer ends of the blades, so that the blades are housed within the ring 9 which is of a width at least equal to the 100 thickness of the fan as shown in Figure 1. If desired, the inner face of the ring may be covered with a wire mesh provided with an aperture through which the hub 4 of the fly wheel may be passed, so as to preclude 105 the hands from being slipped in from the

side of the fan, but, in practice, we find that this is not essential. Moreover, both faces of the fan may be covered with a wire mesh to preclude the fabric from being sucked 5 into the fan by the suction produced by the blades thereof, during the rapid revolving of the fan.

It will be apparent from the foregoing description, that we have produced a fan for 10 sewing machines, which is entirely self contained and serves, in itself, as a guard against accident or injury to the hands of an operator. The guard in no wise encumbers the table of the machine and is of such 15 compact nature that it does not materially add to the length of the machine. In practice, the thickness through the fan may be even less than that shown in the drawings, so that minimum space is taken up by the 20 fan, in contradistinction to the relatively great space occupied by the guards of previous constructions.

Having thus fully described the invention, what we claim as new and desire to secure by Letters Patent is:

A sewing machine attachment embodying 25 a fan provided with a split hub adapted to fit over the hub of the fly wheel of the machine, a clamping screw for contracting the hub of the fan to grip the hub of the fly 30 wheel tightly for the purpose of supporting the fan thereon, and a solid, smooth-faced annular band, surrounding the outer ends of the blades of the fan and attached to and carried by said blades, said band being at 35 least as wide as the thickness of the fan so as to completely overlie the fan and serve as a protector to preclude the inadvertent engagement of the hands of the operator 40 with the fan blades.

In testimony whereof, we have signed our names to this specification.

EGIDIO DELIA.
VINCENT CORRADO.
